POSTHOLE DIGGER

Lloyd L. Grosshart, Boicourt, Kans.

Application April 26, 1946, Serial No. 665,097

2 Claims. (Cl. 74—22)

1

This invention relates to an improved digging apparatus, and more particularly to an improved power transmitting system for a digging apparatus.

The invention is particularly adapted to be used in connection with a mobile power unit such as a tractor or other power plant.

Drilling machines of the type referred to are well known. They are driven by mobile power units in which a drill or auger is attached to the power unit and is driven thereby and moved about therewith from place to place. Such machines heretofore have been handled with manual means for elevating and lowering, or feeding, the drill or auger, resulting in much expenditure of labor and great loss of time not only in the actual boring of the holes, but in putting the apparatus in condition for removal to another site of operation. Thus in a boring machine as heretofore in general use, it has been necessary to employ two or more men in order to accomplish the feeding or elevating of the boring device while the same is being turned.

One object of the invention is to provide a power transmitting means for a digging or boring apparatus which is adapted for attachment to any of numerous types of mobile power units to be carried and operated thereby, and which can readily be detached therefrom when it is desired to use the power unit for other purposes.

Another object is to provide a power transmitting means for a digging (boring) apparatus carried and operated by a mobile power unit and controlled entirely from a single point of operation for both the power unit and the digging apparatus.

The above and other objects are attained by the provision of a digging apparatus adapted to be detachably secured to a mobile power unit, such as a tractor, and provided with a boring device having means whereby all the operations of the same can be controlled from the driver's seat.

My invention is exemplified in the following description and illustrated in the accompanying drawings, in which:

Figure 1 is a side elevation of the apparatus, partly broken away.

Fig. 2 is an end elevation of the invention.

Fig. 3 is a side view of the driving means by which the digging apparatus is driven from the mobile unit.

Fig. 4 is a view of the clutch mechanism.

Fig. 5 is a plan view partly broken away of the stop-and-go nut mechanism.

2

Fig. 6 is a section taken along line 6—6 of Fig. 4, the threaded shaft being omitted.

Fig. 7 is a partial elevation showing the clutch mechanism in the digging or advancing position.

Fig. 8 is a partial elevation showing the clutch mechanism in the elevating or retracting position.

Fig. 9 is an enlarged fragmentary plan view of the clutch braking mechanism.

Fig. 10 is a fragmentary side elevational view of a modified form of clutch mechanism.

As shown in the drawings, a supporting framework 1 is provided by which the digging apparatus as a whole is secured in any convenient manner to a mobile power unit 2, such for example as a tractor.

The digging apparatus may take the form of a drill or auger 3 which is removably secured by a nut 4 to the lower extremity of a threaded shaft 5 which extends upwardly through rotating mechanism therefor, comprising the clutch 6, bevel gear 7, clutch 8, and stop-and-go-nut 9, as will be best seen from an inspection of Figs. 4 and 6.

Fig. 10 is a fragmentary side elevational view of a modified form of clutch mechanism.

As shown in the drawings, a supporting framework 1 is provided by which the digging apparatus as a whole is secured in any convenient manner to a mobile power unit 2, such for example as a tractor.

The digging apparatus may take the form of a drill or auger 3 which is removably secured by a nut 4 to the lower extremity of a threaded shaft 5 which extends upwardly through rotating mechanism therefor, comprising the clutch 6, bevel gear 7, clutch 8, and stop-and-go-nut 9, as will be best seen from an inspection of Figs. 4 and 6.

The bevel gear 7 receives its power from the bevel gear 10 mounted on a horizontal shaft 11, which carries at its opposite end a cog wheel 12 which is in turn rotated by the chain 14.

As a safety measure the cog wheel 12 is covered by a cover 15.

The chain 14 passes over a lower cog wheel 16 mounted on a shaft 17 supported in bearings 18 and 19, seated upon the frame work 1 as best can be seen in Fig. 3.

Shaft 17 is coupled by a universal joint 20 to a slip clutch 21 which in turn is attached to universal joint 22. The universal joint 22 is removably connected to the power take-off of tractor 2 in some convenient manner, such as by means of the socket 23.

The clutch 6 is slidable up and down on the shaft 5 to which it is keyed. The threaded shaft 5 is preferably provided with a continuous keyway 24. The clutch 6 has teeth 25 adapted for interengagement with complementary teeth 26 on the lower side of the bevel gear 7, and is adapted to be moved into and out of engagement therewith by means of the lever 27. Lever 27 is pivoted at 28 to the framework 1 and is retained in either of its operative positions by a support 29.

A brake lever 30 has a notch 31 and 31^a defining a lug 30^a at its end for engagement between the teeth 25 of the clutch 6, in order to hold the clutch 6 against rotation in the operative position of the brake. The brake lever 30 is shown in solid lines

in operative position in Fig. 9, and in dotted lines in inoperative position.

Bevel gear 7 is freely rotatable on shaft 5.

A clutch 8 is keyed upon a sleeve 32 formed on the gear 7, and is provided with teeth 33 which are engageable with complementary teeth 34 formed on the stop-and-go nut 9. The clutch 8 is operated by lever 38 pivoted at 39 on the bracket 37.

Stop-and-go-nut 9 is threaded upon the shaft 5, and is held in place by a sleeve 35 with enclosed ring 36. The sleeve 35 is secured to the framework 1 by means of the braces 31.

A brake mechanism operated by the clutch 8 is provided for the stop-and-go nut 9. This brake mechanism comprises a member 40 pivoted upon the clutch 8, and extending upwardly through a housing 41 on the sleeve 35 to terminate in an angularly horizontally projecting portion 42.

The horizontally projecting portion 42 is adapted to engage teeth 43 on the top of the stop-and-go nut 9, in the operative position of the brake mechanism.

The shaft 5 is steadied in the framework 1 by a brace 44 which is secured to a bearing 45 beneath the clutch member 6.

In utilizing the invention, the mobile unit 2 carrying the digging apparatus is brought to a location where it is desired to dig a hole, with the boring device in elevated or retracted position.

To operate the digging apparatus, the lever 30 is moved so that the notch 31 is out of engagement with the teeth 25 with the teeth 26 of gear 7. The clutch 8 is moved down by lever 38, disengaging the teeth 33 from teeth 34 of the stop-and-go nut 9, and bringing the projection 42 of the brake mechanism into engagement with the teeth 43 of the stop-and-go nut 9, so that the latter cannot rotate. The shaft 5 will then be turned by the gear 7, and due to the fact that stop-and-go nut 9 is held stationary, the shaft 5 will feed downwardly as it rotates, causing the drill 3 to dig the hole.

At the completion of a boring operation the clutch 6 is moved by lever 27 to disengage teeth 25 from teeth 26, thus disconnecting clutch 6 from the rotating motion of gear 7. The lever 30 is then moved to engage the notch 31 with teeth 25. The clutch 6 is then held against rotation. The clutch 8 is raised by the lever 38, engaging the teeth 33 with the teeth 34 of the stop-and-go nut 9, and raising the projection 42 of the brake mechanism out of engagement with teeth 43 of the stop-and-go nut 9, thus permitting the stop-and-go nut 9 to rotate freely.

Rotation of the gear 7 and the clutch 8 therewith in this condition of the apparatus will rotate the stop-and-go nut 9, and due to the fact that shaft 5 is held against rotation by clutch 6, the shaft will be raised and thus withdraw the drill 3 from the hole.

It will of course be understood that the levers 27, 30, and 38 may be extended and are conveniently brought to some location in close proximity to the driver's seat of the mobile power unit so that all operations of the apparatus can be controlled from one point by a single operator.

It should be pointed out that the drill 3 being easily detachable from the shaft 5 by the nut 4, may be removed and repaired or replaced when worn or damaged, or other digging means of equivalent character substituted therefor.

It will thus be seen that the invention as hereinbefore described provides an improved digging

apparatus of simple design and rugged construction, adapted to bring about a substantial saving in time and labor in the digging of post holes or other boring operations.

In Figure 10 there is shown a modified form of clutch wherein the shaft 5a carries a clutch element 6a having teeth 6b at its lower end which are adapted to engage the tooth portion 45b of the bearing 45a which is similar to the bearing 45 described above. This clutch mechanism merely adds another set of teeth 6b and 45b at the bottom of the clutch element 6a and at the top of the bearing bracket 45a, so that these teeth 6b and 45b will automatically engage when the lever 30 is in a raised position. In this form, the lever 30 is eliminated.

What I claim is:

1. In a power transmitting system for a digging apparatus, a source of power, a threaded shaft, mechanism operable to connect said source of power with said shaft, said mechanism comprising a driving gear rotatable on said shaft and having depending spaced clutch teeth, a first clutch operable to connect said gear with said shaft and having upstanding spaced clutch teeth adapted to fit between the clutch teeth of said gear to provide connection therebetween, a brake lever mounted for movement toward and away from said clutch, a lug carried by said brake lever and adapted to be moved into a fitting engagement between the teeth of said clutch for holding said clutch against rotation, a stop-and-go nut threaded on said shaft, a second clutch operable to connect said gear with said stop-and-go-nut, brake means operable to prevent rotation of said stop-and-go nut, and means for bringing said last mentioned brake means into operating position with said stop-and-go nut upon release of said second clutch.

2. In a power transmitting system for a digging apparatus, a source of power, a threaded shaft, mechanism operable to connect said source of power with said shaft, said mechanism comprising a driving gear rotatable on said shaft and having depending spaced clutch teeth, a first clutch operable to connect said gear with said shaft, means to prevent rotation of said first clutch, a stop-and-go nut threaded on said shaft, a second clutch operable to connect said gear with the stop-and-go nut, the stop-and-go nut having protruding teeth, a guide for said nut, a brake mechanism comprising a member slidably extending through said guide and secured at one end to said second clutch, said member of said brake mechanism having an angular portion normally overhanging the teeth of said stop-and-go nut, and means for simultaneously moving said second clutch out of engagement with said stop-and-go nut and moving the angular portion of the brake mechanism into an interfitting position between the teeth of the stop-and-go nut to hold said nut against rotation.
